UNITED STATES PATENT OFFICE

ARTHUR J. COLLINS, OF DETROIT, MICHIGAN

MACHINE FOR TREATING BELTS

Application filed March 14, 1927. Serial No. 175,368.

The invention relates to leather working machines and particularly to machines for finishing belts, straps and similar articles. The invention deals particularly with a machine which will with one passage of the strap through the machine perform various operations upon the strap for finishing the same. Heretofore the various operations above referred to were accomplished only after passing the strap through a number of operations performed by hand or by a plurality of separate machines. This particular arrangement involved an expensive and unsatisfactory method. The present invention contemplates eliminating these disadvantages by combining into one machine means whereby the edges of the strap may be trimmed, burnished and dyed.

The invention contemplates other objects, advantages and many novel details of construction, all of which will be made more apparent as this description proceeds, especially when considered in connection with the accompanying drawings wherein—

Figure 1 is a top plan view of the machine embodying my invention;

Figure 2 is a side elevation thereof;

Figure 3 is a sectional view taken substantially on line 3—3 of Figure 2;

Figure 4 is a sectional view taken on line 4—4 of Figure 1;

Figure 5 is a sectional view taken substantially on the line 5—5 of Figure 1;

Figure 6 is a sectional view taken on line 6—6 of Figure 1;

Figure 7 is a sectional view taken on the line 7—7 of Figure 1;

Figure 8 is a sectional view taken substantially on the line 8—8 of Figure 1;

Figure 9 is a sectional view taken on the line 9—9 of Figure 1;

Figure 10 is an end elevation of the machine;

Figure 11 is a detailed perspective view showing one of the cutters and the particular means for adjusting the amount of trim;

Figure 12 is a sectional view taken substantially on the line 12—12 of Figure 1;

Figure 13 is a sectional view taken on the line 13—13 of Figure 1;

Figure 14 is a sectional view taken on the line 14—14 of Figure 12;

Figure 15 is a top plan view of the receiving mechanism;

Figures 16 and 17 are detailed views of the 55 adjustable bracket bearing.

Referring now to the drawings, in which like characters of reference designate corresponding parts throughout the several views, the numeral 1 indicates the frame of the machine having a base 2 and a table 3 supported above the base by suitable uprights 4 and 5 arranged at opposite ends of the frame. The table 3 is preferably rectangular and is provided with a longitudinally extending way 60 secured to the upper face of the table and constituting a support for the conveyor chain 7. The conveyor chain is preferably an endless chain and is mounted upon sprocket wheels 8 and 9, which in turn are mounted 65 on the shafts 10 and 11 journaled in the upright members 4 and 5 respectively. The sprocket wheel 8, as shown in Figure 4 of the drawings, is formed with a pair of flanges 12 disposed upon opposite sides of and having a substantially greater diameter than the sprocket so as to extend into close proximity to a guide roll 13 keyed to the shaft 14. This latter shaft is preferably power driven 70 and has mounted upon one end thereof a gear 15 meshing with and driven by a gear 16 mounted on the shaft 10. Positioned substantially below this shaft is a third shaft 17 journaled in the upright member 4 and carrying the pulley 18. The shaft 17 is also 75 power driven and is provided with a gear 19 meshing with the gear 16. A belt 20 extends around the pulley 18 and around the pulley 21 loosely mounted on the shaft 22 carried by the upright member 5. The pulley 21 is held from longitudinal movement with respect to the shaft by means of collars 22'. A second belt 23 is arranged below the belt 20 and extends around the pulleys 24 and 25 carried respectively by the upright 80 members 4 and 5. The pulleys 24 and 25, as shown in Figures 12 and 13 of the drawings, are preferably frictionally driven, owing to the fact that the belt 23 frictionally engages the power driven belt 20. For driving the 85

mechanism heretofore set forth a pulley 26 is mounted upon a shaft 27 rotatively and slidably mounted within the shaft 28 and carrying at the forward end thereof a suitable clutch member 29. The shaft 28 is journaled in bracket bearings 30 and 31 mounted upon the base 2 of the machine and carries at the forward end thereof a clutch member 32 engageable with the clutch member 29 for actuating the shaft. Journaled upon the shaft 28 is a pair of sprocket wheels 33 and 34 connected respectively by means of the sprocket chains 35 and 36 to the sprocket wheels 37 and 38 mounted upon the ends of the shafts 10 and 11 respectively.

The device for receiving and starting a strap in the machine is shown best in Figures 4 and 15 and comprises a pair of plates 40 and 41 spaced from each other a sufficient distance to allow the straps to pass therebetween. The particular means for securing the plates in spaced relation to each other, as shown in Figure 15, comprises the spacer members 42 and 43, which in addition to performing the above function serves to initially guide the strap into the machine. The plate 41 is preferably formed with a longitudinally extending slot 44 providing an unobstructed passage for the conveyor chain 7. The edge 45 of the plate 41 terminates short of the guide roll 13 and is formed with a pair of spaced slots or passages 46, allowing the barbs 47, which are formed integral with one of the links of the chain 7, to pass therethrough. In a like manner the guide roller 13 is formed with circumferential grooves 47' for permitting the passage of the barbs 47. For limiting the amount of initial feed of the strap a pair of dogs 48 and 49 are disposed between the plates 41 and 50 directly in rear of the top plate 40. As shown, these dogs are pivotally mounted upon the bottom plates 41. The dogs 48 and 49 are yieldably held against the rear edges of the spacers 42 and 43 by means of the springs 52 and 53 positioned below the plate 41 and having one end anchored thereto and the opposite end secured to the downwardly extending projections 54 and 55 respectively on the dogs 48 and 49. With this arrangement the strap is fed into the machine until the forward edge thereof engages the dogs 48 and 49 and is held in this position until the barbs 47 pierce one end of the strap, whereupon the dogs are forced outwardly to permit the conveyance of the strap through the machine. It will be noted from Figure 4 of the drawings that the dogs not only function as a stop for the strap, but also yieldably engage the side edges 56 of the strap for preventing any lateral movement thereof. Any tendency of the strap to buckle is also prevented by reason of the power driven guide roll 13 contacting with the top edge of the strap substantially throughout the width thereof.

The first operation on the strap after it is fed into the machine is the trimming. This operation is accomplished by two separate devices similar in construction but mounted upon opposite sides of the table and adapted to trim the opposite edges of the belt. As shown in Figure 1 of the drawings, a pair of knives 56 and 57 having cutting edges 58 are adjustably mounted upon the table of the machine on opposite sides of the strap by means of the slotted brackets 59 and studs 60 secured to the table and engageable in the slots of said brackets. These knives are preferably spaced longitudinally from each other and are formed with longitudinally extending grooves 61 in the inner faces thereof of sufficient width to receive the side edges of the strap. Thus the cutters in addition to trimming the edges of the strap also assist in guiding the strap during the trimming operation. For supporting the strap through the trimming operation a pair of plates 62 and 63 are mounted upon the table on opposite sides of the ways 6 and as shown in Figure 5 of the drawings, these plates are formed with a pair of ways 64, the upper edges of which project beyond the ways 6 a sufficient distance to permit the strap to clear the chain 7. In order to prevent the strap from buckling or weaving, I provide the guide rolls 65 and 66 rotatably and slidably mounted upon the shafts 67 and 68 respectively. These shafts as shown in Figures 1 and 5 of the drawings are rigidly mounted upon the brackets 69 and 70 secured to the table upon opposite sides of the strap. The guide rolls 65 and 66 are spaced from the ways 64 a sufficient distance to permit the passage of the strap and are formed with circumferential grooves 71 through which the barbs pass. For insuring an even trim upon both sides of the strap the guide rollers 65 and 66 are formed with flanges 72 and 73 respectively arranged to engage the opposite edges of the strap directly opposite the cutting edges 58 of the cutters 56 and 57. Springs 74 are positioned between the flanges 72 and 73 and their respective brackets 69 and 70 for normally urging the flanges into engagement with the opposite edges of the strap and consequently urging the strap into engagement with the cutters 56 and 57. These springs, however, are not of sufficient strength to move the strap into engagement with the cutters with any degree of force, but merely exert an even pressure upon the flanges and accordingly on the strap to insure a proper trim upon the side edges thereof. For adjusting the amount of trim a pair of blocks 75 and 76 are pivoted upon the table on opposite sides of the strap. As shown in Figure 11, these blocks are formed with undercut portions forming shoulders 77 adapted to engage the strap for guiding the same preparatory to the trimming operation inasmuch as the strap is held in position by the dogs 48 and 49.

much as the blocks are positioned forwardly of the cutters. For accomplishing the adjustment of the blocks I provide the adjusting screws 78 and 79 threadedly engaging the upstanding flanges 80 and 81 respectively of the plates 62 and 63. The ends of the adjusting screws are adapted to engage the outer faces of the blocks at a point substantially offset from the pivots 82 and 83. Thus when it is desired to decrease the amount of trim, the blocks 75 and 76 are rocked about their pivots by means of the adjusting screws 78 and 79, thus moving the strap against the tension of the springs 74 in a direction away from the cutters.

The next operation to be performed upon the strap is the burnishing and rounding of the trimmed edges. The particular mechanism for accomplishing this result comprises a plurality of burnishing wheels 84 arranged upon opposite sides of the strap and having circumferential grooves 85 in the periphery thereof engageable with the edges of the strap. As shown in Figures 2, the burnishing wheels are mounted upon the upper ends of the vertical shafts 86 revolvably contained within the bracket bearings 87 adjustably and pivotally mounted upon opposite sides of the table by means of the pivot pins 89. With this particular arrangement the distance between the oppositely disposed burnishing wheels 84 is automatically adjusted by the passing strap. In other words, if a strap is conveyed through the machine having a slightly greater width than the standard strap, the burnishing wheels will be forced outwardly against the tension of the springs 90. For limiting the inward movement of the burnishing wheels adjustable stops 90' threadedly engage the brackets and abut against the opposite edges of the table. For actuating the burnishing wheels I provide the spiral gears 91 mounted upon the lower ends of the vertical shaft 86 and meshing with the spiral gears 92 journaled upon the horizontal shafts 93. The shafts 93, four in number, preferably extend transversely of and beneath the table 3 and are journaled in the depending bracket bearings 94 secured to the table. As will be noted from Figure 3 the shafts 93 are operatively connected to each other by means of sprocket wheels 95 and sprocket chains 96. One of these shafts 93 preferably projects beyond the table of the machine and has mounted thereon a gear 97 meshing with a gear 98 mounted on the shaft 28. The gear 98, as shown, is considerably larger than the gear 97. Consequently the shaft upon which the gear 97 is mounted is rotated at a substantially higher velocity than the shaft 28 and inasmuch as the ratio between the sprockets 33-37 and 34-38 for driving the conveyor chain 7 is smaller than the ratio between the gears 98 and 97, the burnishing wheels will be driven

at a much higher rate of speed than the speed of the passing strap thus giving the desired polish to the edges of the strap preparatory to receiving the dye.

The next operation to be performed on the strap is the dyeing or coloring of the edges. For this purpose two sets of flanged rollers 97' are arranged upon opposite sides of the strap and are mounted upon the upper ends of the shafts 98', which in turn are journaled in adjustable bracket bearings 99. These bracket bearings are similar in construction to the bracket bearings 87 and are pivotally secured on the table 3 by suitable pivot pins 100. Thus it will be seen that the bracket bearings 99 are also automatically adjustable. Consequently any slight variation in the width of the strap is compensated for by the passing strap. Mounted upon the upper ends of the brackets 99 and surrounding the rollers 97' are suitable troughs 101 having depressed portions 102 adapted to receive the dye. Mounted within the depressed portions 102 directly in front of and contacting with the rollers 97' are suitable dye-carrying rolls 103. These rolls as well as the rolls 97' are provided with an absorbent rim. With this arrangement the rollers 102 will absorb a certain amount of dye and distribute it to the rollers 97', which are yieldably forced against the edges of the strap by reason of the coil springs 104 having the opposite ends thereof anchored upon the table and bracket respectively. Thus the dye is evenly distributed upon the edges of the strap. As shown in Fig. 8, the inner edges of the trough constitute a seat for the strap through the coloring process. The shafts 98' preferably have mounted upon the lower ends thereof the pulleys 105. The particular means for driving the pulleys 105, and consequently the rolls 97', is shown best in Figures 2, 3 and 8 and comprises a gear 106 mounted upon one end of the shaft 11 and meshing with the gear 107 keyed upon the shaft 108 journaled in the upright member 5. The shaft 108 is also provided with a sprocket wheel 109 connected to a sprocket 110 mounted upon the shaft 22 by means of a chain 111. Secured to the outer end of the shaft 22 is a spiral gear 112 meshing with a spiral gear 113 mounted upon the vertical shaft 114 having one end journaled in a bracket 115 and the opposite end journaled in the table and provided with a pulley 116 arranged in substantially the same plane as the pulleys 105 and connected thereto by means of the continuous belt 117.

This belt is provided with sufficient play to permit the desired adjustment of the rollers 97'. The rollers 97' are adapted to revolve at a much slower rate of speed than the speed of the passing strap inasmuch as the gear 107 mounted upon the shaft 103 is considerably larger than the gear 106 mounted upon the shaft 11. For holding the strap in horizon-

tal position on the conveyor chain 7 as it is being conveyed through the burnishing and dyeing mechanism, I provide a holding belt 118 engaging the top face of the strap and extending around the pulleys 119, 120 and 121. 5 The pulley 119, as shown in Figure 1 of the drawings, is mounted directly above the strap on the shaft 122 journaled in a bracket 123 secured to the table of the machine forwardly of the burnishing wheels 84. The second pulley 120 is journaled upon a shaft 124 positioned substantially to the rear of the upright 5 in direct alignment with the pulley aforesaid. Suitable brackets 126 are secured to the upright member 5 for supporting the shaft 124. 10 The third pulley 121 is journaled upon the shaft 108. With this arrangement the strap is accurately guided during its travel about the sprocket 9. As shown in Figure 12 of the drawings, the means for deflecting and separating the strap from the conveyor chain 7 comprises a deflector 128 secured to the front face of the upright member 4 and having a curved surface corresponding to the curvature of the pulley 18 and extending into close proximity thereto. The deflector is further provided with the finger 129 of a width substantially less than the distance between the spaced barbs 47. Thus when the 15 barbs reach the position shown in Figure 12, the finger will project between the chain 7 and the strap, consequently disengaging the latter from the barbs. The strap will then be conveyed around the pulley 18 between the belts 20 and 23 and discharged from the machine thoroughly dried. In order to insure a 20 thorough drying of the straps I provide a housing 130 and a suitable heating unit, herein shown as a gas pipe 131 positioned within the housing. As shown in Figure 7 the housing is secured to the base 2 of the machine and extends over the lower portion of the conveyor chain 7, thus completely encasing the belts 20 and 23.

40 While it is believed that the operation of the machine will be thoroughly understood from the foregoing description, a brief outline thereof will be given. A strap is fed into the machine until the forward edge engages the 45 spring-influenced dogs 48 and 49 and is held in this position until the barbs 47 carried by the conveyor chain 7 pierce the edge of the strap and convey the same with the assistance of the power driven roll 13 into engagement 50 with the cutters 56 and 57 for trimming the opposite sides of the strap. The strap is then fed through the burnishing wheels, which, as set forth above, rotate at a substantially greater speed than the speed of the strap. 55 Thus the edges of the latter are adequately polished and rounded preparatory to receiving the dye which is applied to the edges of the strap by the disks 97' rotating at a substantially slower rate of speed than the speed 60 of the passing strap, thus insuring a proper

application of the dye and eliminating any tendency of the dye to splatter and spot other portions of the strap. The strap is then conveyed through the housing 130 back to the front of the machine where it is detached from the barbs 47 and is passed around the pulley 18 back through the housing to the rear of the machine, where it is discharged. 70

What I claim as my invention is:

1. In a leather strap finishing machine, the combination with a frame having a table, of cutters adjustably mounted upon opposite sides of the table and engageable with the side edges of the strap for trimming the same, and means for adjusting the amount of trim of said strap including blocks pivoted upon the table and having a portion extending over the strap for holding the same substantially flat. 75

2. In a leather strap finishing machine, the combination with a frame having a table, of means for feeding the strap through the machine including a chain having barbs integral with and projecting upwardly from one of the links of said chain, and means arranged in the path of travel of the strap for holding the latter in a predetermined position to be engaged by said barbs. 85

3. In a leather strap finishing machine, the combination with a frame having a table, of cutters mounted upon opposite sides of the table and engageable with the side edges of the strap for trimming the same, blocks pivoted upon said table forwardly of said cutters, and means for adjusting said blocks to move the strap away from said cutters including a member engageable with the block at a point offset from the pivotal connection thereof with the table. 95

4. In a leather strap finishing machine, the combination with a frame having a table, of cutters arranged in spaced relation upon opposite sides of said table and engageable with the opposite side edges of the strap for trimming the same, and means exerting a yieldable pressure upon the side edges of said strap directly opposite the cutting surfaces of said cutters for normally urging the opposite side edges of the strap into engagement with said cutters. 105

5. In a leather strap finishing machine, the combination with a frame having a table, of means for trimming the opposite side edges of the strap including cutters adjustably mounted upon opposite sides of the table, rollers positioned above said strap having oppositely disposed flanges engageable with the side edges of the strap opposite said cutters, and yieldable means engageable with said flanges normally urging said strap into engagement with said cutters. 115

6. In a leather strap finishing machine, the combination with a frame having a table, of cutters arranged upon opposite sides of the table and engageable with the opposite side 120

125

130

135

- edges of the strap for trimming the same, said cutters having longitudinally extending grooves in the inner faces thereof of sufficient width to receive the side edges of the strap for preventing any lateral shifting of the strap, rollers rotatively and slidably mounted above said strap having portions engageable with the upper face of the strap to maintain the same substantially flat and having other portions engageable with the side edges of the strap opposite said cutters, and yieldable means engageable with said rollers for normally urging said strap into engagement with said cutters. 5
10. In a leather strap finishing machine, the combination with a frame, of a device positioned upon the forward end of said frame for receiving and starting a strap, said device comprising upper and lower plates spaced from each other a sufficient distance to allow the passage of said strap, and means for limiting the inward movement of said strap including spring influenced dogs pivotally mounted upon opposite sides of the lower 20 plate. 25
11. In a leather strap finishing machine, the combination with a frame, of a device positioned upon the forward end of said frame for receiving and starting a strap, said device comprising upper and lower plates spaced from each other a sufficient distance to allow the passage of said strap, dogs pivotally mounted upon opposite sides of said lower plate having portions extending into the path 30 of travel of said strap, spacers positioned between said plates constituting means for guiding said straps into engagement with said dogs, and yieldable means normally urging said dogs into engagement with said spacers for limiting the inward movement of 35 said strap. 40
12. In a leather strap finishing machine, the combination with a frame, of a chain for feeding the strap through the machine having barbs integral with and projecting upwardly from one of the links of said chain, a device positioned upon the forward edge of said frame for receiving and starting a strap, dogs pivotally mounted upon said device having portions extending into the path 45 of travel of said strap, and yieldable means engageable with said dogs normally urging the dogs into engagement with the forward end of said strap for holding the same in a position to be engaged by said barbs. 50
13. In a leather strap finishing machine, the combination with a frame, of means for feeding and guiding the strap including a sprocket wheel carried by said frame and having flanges engageable with the bottom surface of said strap, and a power driven guide roller positioned above said flanges and engageable with the top surface of said strap substantially throughout the width thereof. 55
14. In a leather strap finishing machine, the combination with a frame, of means for feeding the strap through the machine including a chain carrying barbs, a sprocket wheel for said chain having flanges of substantially a greater diameter than the sprocket engageable with the bottom surface of the strap, and a guide roller carried by said frame above the sprocket wheel and engageable with the top surface of said strap for maintaining the same substantially flat and assisting in the initial feed of the strap, said guide roller having circumferential grooves permitting the passage of said barbs. 60
15. In a leather strap finishing machine, the combination with a frame having a table, of bracket bearings pivotally mounted upon said table, dyeing rollers mounted upon said brackets, and troughs surrounding said rollers and carried by said bracket bearings. 65
16. In a leather strap finishing machine, 130
- slot permitting the passage of said strap, and dogs mounted upon the last mentioned plate on opposite sides of said slot and having portions extending into the path of said strap for holding the same in a position to be engaged by said feeding means. 70
17. In a leather strap finishing machine, the combination with a chain for feeding the strap through the machine having barbs integral with and projecting upwardly from one of the links of said chain, of a device positioned upon the forward end of the machine for holding the strap in a position to be engaged by said barbs, and means for holding said strap substantially horizontal while being fed through the machine including rollers engageable with the top surface of the belt and having circumferential grooves in the periphery thereof permitting the passage of said barbs. 75
18. In a leather strap finishing machine, the combination with a frame, of a device positioned upon the forward end of the frame for receiving the strap including upper and lower spaced plates, means for feeding the strap through the machine including a chain and barbs carried by said chain, one of said plates having a longitudinally extending slot for receiving said chain and having spaced passageways permitting the passage 80 of the barbs, and means positioned upon said device for holding the forward edge of said strap over the passageways aforesaid to be engaged by said barbs. 85
19. In a leather strap finishing machine, the combination with a frame, of means for feeding and guiding the strap including a sprocket wheel carried by said frame and having flanges engageable with the bottom surface of said strap, and a power driven guide roller positioned above said flanges and engageable with the top surface of said strap substantially throughout the width thereof. 90
20. In a leather strap finishing machine, the combination with a frame, of means for feeding the strap through the machine including a chain carrying barbs, a sprocket wheel for said chain having flanges of substantially a greater diameter than the sprocket engageable with the bottom surface of the strap, and a guide roller carried by said frame above the sprocket wheel and engageable with the top surface of said strap for maintaining the same substantially flat and assisting in the initial feed of the strap, said guide roller having circumferential grooves permitting the passage of said barbs. 95
21. In a leather strap finishing machine, the combination with a frame having a table, of bracket bearings pivotally mounted upon said table, dyeing rollers mounted upon said brackets, and troughs surrounding said rollers and carried by said bracket bearings. 100
22. In a leather strap finishing machine, the combination with a frame having a table, of bracket bearings pivotally mounted upon said table, dyeing rollers mounted upon said brackets, and troughs surrounding said rollers and carried by said bracket bearings. 105
23. In a leather strap finishing machine, the combination with a frame having a table, of bracket bearings pivotally mounted upon said table, dyeing rollers mounted upon said brackets, and troughs surrounding said rollers and carried by said bracket bearings. 110
24. In a leather strap finishing machine, the combination with a frame having a table, of bracket bearings pivotally mounted upon said table, dyeing rollers mounted upon said brackets, and troughs surrounding said rollers and carried by said bracket bearings. 115
25. In a leather strap finishing machine, the combination with a frame having a table, of bracket bearings pivotally mounted upon said table, dyeing rollers mounted upon said brackets, and troughs surrounding said rollers and carried by said bracket bearings. 120
26. In a leather strap finishing machine, the combination with a frame having a table, of bracket bearings pivotally mounted upon said table, dyeing rollers mounted upon said brackets, and troughs surrounding said rollers and carried by said bracket bearings. 125

the combination with a frame having a table, of bracket bearings pivotally mounted upon said table, troughs positioned upon said bracket bearings, rollers rotatably mounted within said troughs and engageable with the 5 opposite side edges of the strap, said troughs having depressed portions adapted to contain dye, and means positioned within said depressed portion for distributing the dye 10 upon the periphery of the rollers aforesaid.

17. In a leather strap finishing machine, the combination with a frame having a table, of bracket bearings pivotally mounted upon said table, troughs positioned upon said bracket bearings, rollers rotatably mounted 15 within said troughs and having an absorbent rim engageable with the opposite side edges of the strap, said troughs having depressed portions adjacent to said rollers adapted to contain dye, and members arranged within 20 said depressed portion and engageable with the rollers aforesaid for distributing the dye on the periphery of said rollers.

18. In a leather strap finishing machine, the combination with a frame and means for 25 conveying a strap through the machine, of a cutter carried by the frame and engageable with the strap to trim the same, and a roller also carried by the frame and engageable 30 with the strap to guide the same during the trimming operation, said roller being capable of movement transversely of the strap and having a portion engageable with one edge thereof to normally urge the opposite 35 edge into engagement with said cutter.

19. In a leather strap finishing machine, the combination with a frame, of a conveyor carried by said frame for feeding the strap through the machine, and means secured to 40 the frame adjacent the receiving end thereof for limiting the initial feed of the strap and for holding the same in a predetermined position to be engaged by the conveyor.

20. In a leather strap finishing machine, the combination with a frame, of a conveyor 45 mounted upon said frame for feeding the strap through the machine and means secured to the frame adjacent the receiving end thereof for limiting the extent of initial feed 50 of the strap and for holding the same in position to be engaged by the conveyor, said means including a pivotal member having a portion normally disposed in the path of travel of the strap.

21. In a leather strap finishing machine, the combination with a frame, of means positioned upon said frame for feeding a strap 55 through the machine including a chain and a sprocket wheel therefor, said sprocket 60 wheel having flanges at the sides thereof extending beyond the chain and engageable with the strap to guide the same.

22. In a leather strap finishing machine, the combination with a frame, of means for 65 feeding a strap through the machine includ-

ing a chain and sprocket wheel therefor, said sprocket wheel having portions extending beyond the chain and engageable with one side of the strap, and a member carried by the frame above the sprocket wheel aforesaid and arranged to engage the opposite side of the 70 strap.

23. In a leather strap finishing machine, the combination with a frame, and means carried thereby for conveying a strap through the machine, of a bracket bearing carried by the frame, means for applying a fluid to the edges of said strap including a roll journalled within said bracket bearing, and a trough mounted upon said bracket bearing and surrounding said roll and having a portion engageable with the strap to guide the same. 75

24. In a leather strap finishing machine, the combination with a frame and means carried thereby for conveying a strap through the machine, of bracket bearings carried by said frame and disposed upon opposite sides of said strap, means for applying a fluid to the opposite edges of the strap including rolls journalled within said bracket bearings, and troughs secured to the bracket bearings and surrounding said rolls, said troughs having upwardly extending flanges at the inner edges thereof engageable with the strap adjacent the opposite side edges thereof for guiding and supporting the same during the 90 dyeing operation. 95

25. In a leather strap finishing machine, the combination with a frame and means carried by the frame for feeding a strap through the machine, of a bracket bearing carried by the frame, means for applying a fluid to the side edges of the strap including a roller mounted upon said bracket bearing and engageable with the side edges of the strap, and a trough also mounted upon said bracket bearing and surrounding said roller. 100 105

26. In a leather strap finishing machine, the combination with a frame and means carried thereby for feeding a strap through the machine, of a pivotally mounted bracket bearing carried by said frame, means for applying a fluid to the side edges of the strap including a member rotatably mounted upon said bracket bearing, a trough carried by said bracket bearing and surrounding said member, and a roll journalled within said trough and engageable with the member aforesaid for distributing the fluid upon the same member. 110 115

In testimony whereof I affix my signature. 120
ARTHUR J. COLLINS.
